UNITED STATES PATENT OFFICE.

LEO PRANGE, OF BROOKLYN, NEW YORK.

DESIGN FOR A BUTTON.

SPECIFICATION forming part of Design No. 21,320, dated January 26, 1892.

Application filed December 18, 1891. Serial No. 415,554. Term of patent 3½ years.

To all whom it may concern:

Be it known that I, LEO PRANGE, of Brooklyn, Kings county, and State of New York, have originated and produced a new Design 5 for Buttons, of which the following is a specification.

I will describe a button embodying my design.

In the accompanying drawings, Figure 1 is 10 a front view of a circular button embodying my design. Fig. 2 is a perspective side view thereof.

My design comprises triangular groups of 15 jewel-like figures A, arranged with their apices toward one another. Between these groups of jewel-like figures A are triangular surfaces B, which, near the apices of the tri-

angular groups of jewel-like figures, are ornamented by filigree-work C and outside of the filigree-work with circular lines. The 20 edge portion of the button is embellished with representations of rope or cord D.

What I claim, and desire to secure by Letters Patent, is—

The design for a button, as herein shown 25 and described.

In testimony whereof I have signed my name to this specification in the presence of two subscribing witnesses.

LEO PRANGE.
